The ornamental design for a baby bottle with protective lid, as shown and described.

DESCRIPTION

FIG. 1 is a perspective view of a baby bottle with a protective lid according to a first embodiment;

FIG. 2 is a front view of the baby bottle with the protective lid according to the first embodiment;

FIG. 3 is a rear view of the baby bottle with the protective lid according to the first embodiment;

FIG. 4 is a right side view of the baby bottle with the protective lid according to the first embodiment;

FIG. 5 is a left side view of the baby bottle with the protective lid according to the first embodiment;

FIG. 6 is a top view of the baby bottle with the protective lid according to the first embodiment;

FIG. 7 is a bottom view of the baby bottle with the protective lid according to the first embodiment;

FIG. 8 is an exploded view of the baby bottle with the protective lid according to the first embodiment showing the protective lid removed from the baby bottle;

FIG. 9 is a perspective view of a baby bottle with a protective lid according to a second embodiment illustrating a baby bottle with a protective lid having an internal volume that varies from that of the first embodiment;

FIG. 10 is a front view of the baby bottle with the protective lid according to the second embodiment;

FIG. 11 is a rear view of the baby bottle with the protective lid according to the second embodiment;

FIG. 12 is a right side view of the baby bottle with the protective lid according to the second embodiment;

FIG. 13 is a left side view of the baby bottle with the protective lid according to the second embodiment; and,

FIG. 14 is an exploded view of the baby bottle with the protective lid according to the first embodiment showing the protective lid removed from the baby bottle.

The top and bottom views of the baby bottle with the protective lid according to the second embodiment are not shown, as they are identical to the top and bottom views of the baby bottle with the protective lid according to the first embodiment shown in FIGS. 6 and 7, respectively.

The broken lines showing a nipple in FIGS. 8 and 14 illustrate a portion of the article and form no part of the claimed design.
